United States Patent

Des. 235,440
Patented June 17, 1975

235,440

EDUCATIONAL PLUG-IN BOARD

Charles G. Valentine, Stamford, Conn., assignor to
Xerox Corporation, Stamford, Conn.

Filed Apr. 20, 1973, Ser. No. 353,187

Term of patent 14 years

Int. Cl. D19—07

U.S. Cl. D19—62

FIG. 1

FIG. 2

FIG. 1 is a right perspective view of an educational plug-in board showing my new design; and

FIG. 2 is a left perspective view thereof.

The rear of the educational plug-in board not shown is plain and unornamented.

I claim:

The ornamental design for an educational plug-in board, substantially as shown and described.
